UNITED STATES PATENT OFFICE

2,457,864

PURCHASE SHEET MARKING DEVICE

Philip H. Burn, Forest Hills, N. Y.

Application January 8, 1946, Serial No. 639,865

17 Claims. (Cl. 164—112)

1

This invention relates to devices for use in marking by piercing a purchase sheet to indicate purchases to be made. More particularly, the invention deals with a device of the kind defined, wherein a series of purchase sheets are arranged in joined relationship to each other in the device and disposed therefrom one at a time, means being provided in the device for piercing a sheet supported in piercing position, to indicate adjacent the names of articles printed on the sheet, the articles to be purchased, the outer surface of the device having registering names of the articles appearing on the sheet with means for designating articles to be purchased. More particularly, the invention deals with the device of the kind defined, wherein the designating means also forms the sheet piercing means, the device having a manually actuated member for moving the sheet into position to be perforated by said designating means. The novel features of the invention will be best understood from the following description when taken together with the accompanying drawing in which certain embodiments of the invention are disclosed, and in which the separate parts are designated by suitable reference characters in each of the views, and in which:

Fig. 1 is a plan view of the device made according to my invention, with parts of the construction broken away and in section.

Fig. 2 is a section on the line 2—2 of Fig. 1, showing the sheet operating member in normal position.

Fig. 3 is a section on the line 3—3 of Fig. 1.

Fig. 4 is a partial section on the line 4—4 of Fig. 1, on an enlarged scale.

Fig. 5 is a view similar to Fig. 2, showing only a part of the construction, with parts in a different position, the view being on an enlarged scale; and

Fig. 6 is a view similar to Fig. 5, showing the piercing and designating elements in piercing and designating position in full lines, and in normal position, in dot-dash lines.

While my invention deals primarily with devices or apparatus for piercing a purchase sheet to indicate articles to be purchased, in what is commonly referred to as a shopping list, the invention is adaptable for use in piercing strips or sheets of any type or kind, and for any suitable purpose.

In illustrating one adaptation and use of my invention, I have shown in the accompanying drawing an oblong rectangular box or case 10, the top wall of which has an inwardly set rounded portion 11, below and outwardly of which is a

table 12, having an inturned flange portion 13. The table 12 is adapted to support one end portion 14 of a purchasing or shopping sheet 15. At the outer end of the table 12 is a cutter or tear-off edge 16, which may be produced in any desired manner, so as to tear each sheet 15 from adjacent sheets, which in the present construction are arranged in folded relationship to each other, as seen in the stack 15', note Fig. 3.

Arranged in the case 10 adjacent the other end thereof is a transverse frame or supporting rod 17. The outer surface of the rod 17 is rounded, note Fig. 3, to guide the paper sheets 15 as they are drawn in the direction of the forward or table 12 of the casing.

Mounted in the rod 17 and flange 13, is an elongated pivot shaft 18, on which is pivoted a sheet supporting and operating member or platform 19. The member or platform 19 has at one side, an upwardly projecting fingerpiece 20 which extends freely through an opening 21 in the top 22 of the casing 10, and projects above the top 22 sufficiently to provide the necessary operation of the member 19, as later described.

Coupled to the other side of the member 19 is a coil spring 23, secured to the bottom 24 of the case 10, as seen at 25. The spring 23 normally supports the member 19 in the position shown in Fig. 2, this position being maintained by the stop pin 26 on the fingerpiece 20.

Extending longitudinally of the side portion of the member 19, to which the spring 23 is attached, is a series of openings 27 which are arranged beneath and in registering alignment with the corresponding number of elongated apertures 28 in the top wall 22 of the case 10. Extending along the inner surface of the top wall 22 of the case 10 is a downwardly and laterally extending hook-shaped flange 29 having a rounded edge portion 30, the flange forming between the same and the top wall 22 a corresponding longitudinal recess 31. The flange 29 provides means for supporting designating and piercing elements 32 in operative and inoperative positions, as shown in full and dot and dash lines in Fig. 6 of the drawing. One of the elements 32 is arranged within each of the apertures 28, the elements being free to swing upon a pivot rod 33 supported in end walls of the case 10.

Each element is of the same construction, so that the brief description of one will apply to all. Each element 32 has a fingerpiece portion 34 extending through the aperture 28 and projecting above the top 22 of the case. The inner end portion of the element has a downwardly extending

pointed marker or piercer 35 above which is a laterally extending finger portion 36 which projects to one side of the element 32. Projecting from the other side thereof is a spring member 37 having a rounded end 38. The rounded end 38 of the spring member is adapted to operate in conjunction with the flange 29 in supporting each of the elements 32 in the full and dot-dash line positions shown in Fig. 6, the element snapping into either of these positions from a neutral position, such as shown in Fig. 5, which position is illustrated primarily to indicate automatic return of elements to normal position through the means which will now be described.

Supported upon the right side of the member or platform 19, as seen in the drawing, and adjacent the ends of the platform are upstanding spring arms 39, in the upper ends of which is supported a rod 40, which extends longitudinally of the case to a degree greater than the position occupied by the elements 32, as will appear from a consideration of Figs. 1 and 4 of the drawing.

When the member or platform 19 is in its normal position, as shown in Fig. 2, the elements 32 are free to be swung from the normal dot-dash position, as indicated in Fig. 6, to the full line position, as will appear from a consideration of Fig. 2 of the drawing, the fingers 36 clearing the rod 40 in this operation. However, in depressing the fingerpiece 20 to move the same from the position shown in Fig. 2, to that shown in Fig. 6, the rod 40 will ride over the lower bevelled surface 36' of the fingers 36 and extend to the position shown in Fig. 6, thus as the spring 23 returns the member or platform 19 to the position shown in Fig. 2, the downward movement of the rod 40 will engage the fingers 36 of all of the elements 32 which are in the full line position and operate to simultaneously return all of the fingers to the inoperative or dot-dash position of Fig. 6, part of this operation being illustrated in Fig. 5, where one of the elements is shown in what may be termed an intermediate position just prior to the instant that the rod 40 snaps the element to inoperative position and passes below said element.

Supported on the platform 19 adjacent and above the apertures 27 is a comb-like strip 41, the several fingers 42 of which are disposed between the apertures 27 and the elements 32 and serve to free the sheet 15 from the piercers 35 of the elements as the member or platform 19 moves downwardly by the spring 23.

The upper surface 22 of the case 10 has arranged longitudinally thereof a series of titles designating articles, products or objects to be purchased. For illustration, a few of such markings or characterizations are shown at 43 to designate what may be termed a market listing for the purchase of conventional food and other household requirements. A few only of such indicia 43 are shown in Fig. 1, to simplify the illustration. For example, lettuce, matches, meat, milk, nuts, oranges and potatoes.

The sheet 15 also has printed or otherwise arranged thereon identical markings or indicia positioned directly beneath the markings 43, for example, at 44, in Fig. 1, is shown the indicia "at" of the word "meat," as appearing on the sheet 15 by breaking away the top wall 22 of the case 10. This alinement and registration is maintained by registration of the end 15' of the sheet 15 in alinement with the cutter edge 16, note Fig. 3. The markings or indicia, as well as the indicia

44 are in registering alinement with the apertures 28 in the top wall 22 and the apertures 27 in the member or platform 19.

A housewife from time to time through the day, can move the elements 32 to the left to designate purchases which she intends to make when going to the stores. Then when it is desired to proceed to make the purchases, the fingerpiece 20 is depressed, thus moving the right side of the sheet 15 upwardly and passing the piercer points 35 of all of the shifted elements 32 through the sheet 15, as seen at 45, in Fig. 6 of the drawing. It will here be understood that the piercer points 35 of the elements 32 assuming the full line position will be the only elements which mark the sheet and by perforating the same. Upon release of the pressure upon the fingerpiece 20, the spring 23 immediately returns the member 19 to the position of Fig. 2, automatically returning all of the actuated elements 32 to the dot-dash line position of Fig. 6, whereupon the pierced purchase sheet 15 is drawn forwardly through the opening 46 until the end of this sheet registers with the cutter 16, whereupon the advance sheet is torn-off, leaving the next successive sheet in position for piercing, as above indicated.

In practice, the more or less continuous ribbon-like strip from which the separate sheets 15 are ultimately formed, will have either perforations or markings to indicate sheet lengths, and these perforations or markings will be brought into registering alinement with the cutter or tear-edge 16.

Devices of the character described, by reason of the simplicity of construction can be produced for reasonable retail sale, thus placing the device within the reach of substantially all households. It will also be apparent that the device may be utilized as a reminder for making purchases of any type or kind, depending entirely upon the characterizations or indicia employed on the device.

It will be understood that the device under consideration may also be used commercially in piercing sale-slips to simplify the process of conducting sales, particularly in stores where it is customary to write out sale-slips for articles purchased. This procedure would be particularly adaptable in grocery stores where staple items are purchased, and a positive recording will be had at all times of the items purchased. Sales computation can be tabulated on the conventional adding machine, as used in many of the larger establishments of this type and kind. In this procedure, the salesman would simply operate the element 32 to indicate the articles purchased by the customer, then mark the sales-sheet in the manner above indicated, and from this the price tabulation can be made. Such incidentals as the quantity of each item purchased can be readily calculated. The important thing is to indicate on the sales-slip the number of items which have been purchased.

The foregoing is mentioned to indicate one other of the possible uses of the invention.

Having fully described my invention, what I claim as new, and desire to secure by Letters Patent is:

1. A device of the class described comprising an elongated case, a plurality of characterized openings spaced longitudinally of one wall of the case, the case being adapted to support elongated strips, with one end of a strip accessible outwardly of one end of the case, piercing elements pivotally mounted in the case and having fingerpiece portions protruding outwardly through the openings

of said case, each strip having indicia thereon in registering alinement with said piercing elements when the strip has one end thereof accessible through one end of the case, said piercing elements being manually movable into piercing position, manually actuated means in the case for moving said strip into operative engagement with said elements supported in piercing position to pierce the strip in alinement with the indicia thereon registering with said last named elements, means for supporting each piercing element in piercing and non-piercing positions, said last named means comprising a hook-shaped flange extending longitudinally of said openings, and said elements having spring members operatively engaging the flange in supporting said elements in operative and inoperative positions.

2. A device of the class described comprising an elongated case, a plurality of characterized openings spaced longitudinally of one wall of the case, the case being adapted to support elongated strips, with one end of a strip accessible outwardly of one end of the case, piercing elements pivotally mounted in the case and having fingerpiece portions protruding outwardly through the openings of said case, each strip having indicia thereon in registering alinement with said piercing elements when the strip has one end thereof accessible through one end of the case, said piercing elements being manually movable into piercing position, manually actuated means in the case for moving said strip into operative engagement with said elements supported in piercing position to pierce the strip in alinement with the indicia thereon registering with said last named elements, said last named means comprising a platform pivotally mounted in the case, the platform having a plurality of apertures in registering alinement with the openings of the case and the elements movably supported therein, and said elements having end portions adapted to pierce the strip through the apertures of the platform.

3. A device of the class described comprising an elongated case, a plurality of characterized openings spaced longitudinally of one wall of the case, the case being adapted to support elongated strips, with one end of a strip accessible outwardly of one end of the case, piercing elements pivotally mounted in the case and having fingerpiece portions protruding outwardly through the openings of said case, each strip having indicia thereon in registering alinement with said piercing elements when the strip has one end thereof accessible through one end of the case, said piercing elements being manually movable into piercing position, manually actuated means in the case for moving said strip into operative engagement with said elements supported in piercing position to pierce the strip in alinement with the indicia thereon registering with said last named elements, said last named means comprising a platform pivotally mounted in the case, the platform having a plurality of apertures in registering alinement with the openings of the case and the elements movably supported therein, said elements having end portions adapted to pierce the strip through the apertures of the platform, and a spring for returning the platform to a normal position.

4. A device of the class described comprising an elongated case, a plurality of characterized openings spaced longitudinally of one wall of the case, the case being adapted to support elongated strips, with one end of a strip acces-

sible outwardly of one end of the case, piercing elements pivotally mounted in the case and having fingerpiece portions protruding outwardly through the openings of said case, each strip having indicia thereon in registering alinement with said piercing elements when the strip has one end thereof accessible through one end of the case, said piercing elements being manually movable into piercing position, manually actuated means in the case for moving said strip into operative engagement with said elements supported in piercing position to pierce the strip in alinement with the indicia thereon registering with said last named elements, said last named means comprising a platform pivotally mounted in the case, the platform having a plurality of apertures in registering alinement with the openings of the case and the elements movably supported therein, said elements having end portions adapted to pierce the strip through the apertures of the platform, a spring for returning the platform to a normal position, and means on the platform operatively engaging all elements supported in piercing position to return said elements to non-piercing position in the return of the platform to normal position.

5. A strip punching device of the character defined, said device comprising an elongated case, means in the case for supporting an elongated work-strip, the case having, longitudinally of one surface thereof, predetermined indicia, a plurality of piercing elements pivoted directly to the case and arranged longitudinally of the case in registering alinement with the indicia thereon, said elements being normally supported in non-piercing position with respect to said indicia and adapted for manual movement into piercing position therewith in designating selections of predetermined indicia on said case, said means supporting a strip normally in spaced relation to said elements when in piercing position, and a directly manually actuated member protruding through the case for moving said means and a strip supported thereon into position engaging the elements moved into piercing position to pierce in the strip the selection of indicia on said case.

6. A strip device of the character defined, said device comprising an elongated case, means in the case for supporting an elongated work-strip, the case having, longitudinally of one surface thereof, predetermined indicia, a plurality of pivoted piercing elements arranged longitudinally of the case in registering alinement with the indicia thereon, said elements being normally supported in non-piercing position with respect to said indicia and adapted for manual movement into piercing position therewith in designating selections of predetermined indicia on said case, said means supporting a strip normally in spaced relation to said elements when in piercing position, a manually actuated member protruding through the case for moving said means and a strip supported thereon into position engaging the elements moved into piercing position to pierce in the strip the selection of indicia on said case, and means for automatically returning all of said elements to normal position upon completion of the piercing of said strip.

7. A strip punching device of the character defined, said device comprising an elongated case, means in the case for supporting an elongated work-strip, the case having, longitudinally of one surface thereof, predetermined indicia, a plurality of pivoted piercing elements arranged longitudinally of the case in registering alinement

with the indicia thereon, said elements being normally supported in non-piercing position with respect to said indicia and adapted for manual movement into piercing position therewith in designating selections of predetermined indicia on said case, said means supporting a strip normally in spaced relation to said elements when in piercing position, a manually actuated member protruding through the case for moving said means and a strip supported thereon into position engaging the elements moved into piercing position to pierce in the strip the selection of indicia on said case, means for automatically returning all of said elements to normal position upon completion of the piercing of said strip, and means for allowing manual removal of a marked strip from the case and for positioning a successive strip in the case, preparatory for piercing the same.

8. A strip punching device of the character defined, said device comprising an elongated case, means in the case for supporting an elongated work-strip, the case having, longitudinally of one surface thereof, predetermined indicia, a plurality of pivoted piercing elements arranged longitudinally of the case in registering alinement with the indicia thereon, said elements being normally supported in non-piercing position with respect to said indicia and adapted for manual movement into piercing position therewith in designating selections of predetermined indicia on said case, said means supporting a strip normally in spaced relation to said elements when in piercing position, a manually actuated member protruding through the case for moving said means and a strip supported thereon into position engaging the elements moved into piercing position to pierce in the strip the selection of indicia on said case, means for automatically returning all of said elements to normal position upon completion of the piercing of said strip, means for allowing manual removal of a marked strip from the case and for positioning a successive strip in the case, preparatory for piercing the same, and means on said first named means for stripping the sheet from all of said elements.

9. A device of the class described comprising an elongated case, a plurality of characterized openings spaced longitudinally of one wall of the case, a platform in the case adapted to support elongated strips, with one end of a strip accessible outwardly of one end of the case, piercing elements pivotally mounted in the case and having fingerpiece portions protruding outwardly through the openings of said case, each strip having indicia thereon in registering alinement with said piercing elements when the strip has one end thereof accessible through one end of the case, said piercing elements being manually movable into piercing position, manually actuated means projecting through the case for moving said platform and a strip supported thereon into operative engagement with all of said elements supported in piercing position to pierce the strip in alinement with the indicia thereon registering with said last named elements, means for automatically moving the platform and the strip supported thereon out of engagement with said last named elements, and means for returning all of the last named elements into non-piercing position.

10. A device of the class described comprising an elongated case, a plurality of characterized openings spaced longitudinally of one wall of the case, a platform in the case adapted to support

10 elongated strips, with one end of a strip accessible outwardly of one end of the case, piercing elements pivotally mounted in the case and having fingerpiece portions protruding outwardly through the openings of said case, each strip having indicia thereon in registering alinement with said piercing elements when the strip has one end thereof accessible through one end of the case, said piercing elements being manually movable into piercing position, manually actuated means projecting through the case for moving said platform and a strip supported thereon into operative engagement with all of said elements supported in piercing position to pierce the strip in alinement with the indicia thereon registering with said last named elements, means for automatically moving the platform and the strip supported thereon out of engagement with said last named elements, means for returning all of the last named elements into non-piercing position, and means on the case and each element for tensionally supporting each element in piercing and non-piercing positions.

11. A device of the class described comprising an elongated case, a plurality of characterized openings spaced longitudinally of one wall of the case, a platform in the case adapted to support elongated strips, with one end of a strip accessible outwardly of one end of the case, piercing elements pivotally mounted in the case and having fingerpiece portions protruding outwardly through the openings of said case, each strip having indicia thereon in registering alinement with said piercing elements when the strip has one end thereof accessible through one end of the case, said piercing elements being manually movable into piercing position, manually actuated means projecting through the case for moving said platform and a strip supported thereon into operative engagement with all of said elements supported in piercing position to pierce the strip in alinement with the indicia thereon registering with said last named elements, means for automatically moving the platform and the strip supported thereon out of engagement with said last named elements, means for returning all of the last named elements into non-piercing position, means on the case and each element for tensionally supporting each element in piercing and non-piercing positions, said last named means comprising an elongated hook flange on the case, and spring members on each element engaging said flange in both positions of said element.

12. A device for punching an indicia strip having predetermined arrangement of indicia thereon, said device comprising a pivoted platform having a predetermined alinement of apertures therein, a corresponding number of piercing elements pivotally supported in registering alinement with the apertures of said platform, said elements having pronged ends adapted to pass through the apertures in the platform in piercing an indicia strip arranged on the platform over said apertures, means normally supporting all of the elements in non-piercing position, means for normally supporting that part of the platform having the apertures therein in spaced relation to said elements when manually moved into piercing position, means for supporting said elements in the piercing position, and manually actuated means on the platform for moving the apertured portion of the platform in the direction of said elements supported in piercing posi-

tion, and simultaneously piercing a sheet by all of said elements.

13. A device for punching an indicia strip having predetermined arrangement of indicia thereon, said device comprising a pivoted platform having a predetermined alinement of apertures therein, a corresponding number of piercing elements pivotally supported in registering alinement with the apertures of said platform, said elements having pronged ends adapted to pass through the apertures in the platform in piercing an indicia strip arranged on the platform over said apertures, means normally supporting all of the elements in non-piercing position, means for normally supporting that part of the platform having the apertures therein in spaced relation to said elements when manually moved into piercing position, means for supporting said elements in the piercing position, manually actuated means on the platform for moving the apertured portion of the platform in the direction of said elements supported in piercing position, simultaneously piercing a sheet by all of said elements, and means for returning all of said elements to non-piercing position upon release of the platform and movement thereof into normal position.

14. A device for punching an indicia strip having predetermined arrangement of indicia thereon, said device comprising a pivoted platform having a predetermined alinement of apertures therein, a corresponding number of piercing elements pivotally supported in registering alinement with the apertures of said platform, said elements having pronged ends adapted to pass through the apertures in the platform in piercing an indicia strip arranged on the platform over said apertures, means normally supporting all of the elements in non-piercing position, means for normally supporting that part of the platform having the apertures therein in spaced relation to said elements when manually moved into piercing position, means for supporting said elements in the piercing position, manually actuated means on the platform for moving the apertured portion of the platform in the direction of said elements supported in piercing position, simultaneously piercing a sheet by all of said elements, means for returning all of said elements to non-piercing position upon release of the platform and movement thereof into normal position, and means for stripping the pierced sheet from all of said elements in return of the platform to normal position.

15. A device for punching an indicia strip having predetermined arrangement of indicia thereon, said device comprising a pivoted platform having a predetermined alinement of apertures therein, a corresponding number of piercing elements pivotally supported in registering alinement with the apertures of said platform, said elements having pronged ends adapted to pass through the apertures in the platform in piercing an indicia strip arranged on the platform over

said apertures, means normally supporting all of the elements in non-piercing position, means for normally supporting that part of the platform having the apertures therein in spaced relation to said elements when manually moved into piercing position, means for supporting said elements in the piercing position, manually actuated means on the platform for moving the apertured portion of the platform in the direction of said elements supported in piercing position, simultaneously piercing a sheet by all of said elements, means for returning all of said elements to non-piercing position upon release of the platform and movement thereof into normal position, means for stripping the pierced sheet from all of said elements in return of the platform to normal position, and dual means supporting all of said elements in normal non-piercing position.

16. In a device for piercing an elongated strip with piercings extending longitudinally of the strip, said device comprising a frame, a plurality of aligned piercing elements directly pivoted in the frame and adapted for manual movement into piercing and non-piercing positions, dual means supporting the elements in both positions, means for normally supporting a strip to be pierced out of engagement with said elements, when in piercing position, and said last named means being directly manually movable in the direction of said elements in simultaneously passing the elements supported in piercing position through the strip supported on said means.

17. In a device for piercing an elongated strip, with piercings extending longitudinally of the strip, said device comprising a plurality of aligned, pivoted, piercing elements adapted for manual movement into piercing and non-piercing positions, dual means supporting the elements in both positions, means for normally supporting a strip to be pierced out of engagement with said elements, when in piercing position, said last named means being manually movable in the direction of said elements in simultaneously passing the elements supported in piercing position through the strip supported on said means, and means for automatically returning all of said elements to non-piercing position in movement of the last named means and the strip out of engagement with said elements.
